(57) **CLAIM**

The measurement device with multiple defined distances, as shown and described.

DESCRIPTION

FIG. 1 is a perspective upper view of a measurement device with multiple defined distances according to the present invention.

FIG. 2 is a front side view of the measurement device with multiple defined distances of FIG. 1.

FIG. 3 is a rear side view of the measurement device with multiple defined distances of FIG. 1.

FIG. 4 is an upper side view of the measurement device with multiple defined distances of FIG. 1.

FIG. 5 is a bottom side view of the measurement device with multiple defined distances of FIG. 1.

FIG. 6 is a right side view of the measurement device with multiple defined distances of FIG. 1; and,

FIG. 7 is a left side view of the measurement device with multiple defined distances of FIG. 1.
